THREAD HOLDING AND TRIMMING ATTACHMENT FOR LOOMS

Application filed December 7, 1928. Serial No. 324,426.

This invention relates to mechanisms designed to be used in looms to hold filling threads on drop box looms when shuttle is not in operation. Also, to cut threads which extend loosely from the selvage of the fabric.

In weaving pattern fabrics in box looms the changing of the shuttles to produce the required design results in the formation of loose loops of filling attached to the selvage of the fabric at the drop box side of the loom. While many attempts have been made heretofore to cut off these threads or strands of filling automatically during the weaving operation, such attempts have not met with commercial success, so far as we have been able to learn, and it is still the usual practice to cut off such loops by hand.

The present invention deals with this problem and aims to devise a thoroughly practical solution for it.

The nature of the invention will be readily understood from the following description when read in connection with the accompanying drawings, and the novel features will be particularly pointed out in the appended claims.

In the drawings,

Figure 1 is a perspective view of a mechanism embodying this invention;

Fig. 2 is a perspective view of the cutting mechanism shown in Fig. 1;

Fig. 3 is a plan view of the mechanism shown in Fig. 1 for gripping the strand of filling to be trimmed or cut off;

Fig. 4 is a front elevation of the mechanism shown in Fig. 3;

Fig. 5 is a side view of the mechanism shown in Fig. 4 and also shows part of the lay in section;

Fig. 6 is a perspective view showing the rearward surfaces of certain of the parts shown in Figs. 4 and 5; and

Fig. 7 is a sectional view on the line 7-7, Fig. 4.

Referring first to Fig. 1, the drop box of a box loom is indicated at 2, the lay at 3, the lay sword at 4, and the reed at 5, these parts being constructed, arranged and operated in the usual manner. As is well understood by those skilled in this art, the several shuttles

handled by the drop box carrying filling of different colors. When any shuttle is moved into an idle position by the raising or lowering of the box 2 a strand of filling is left running from the fell of the goods to the bobbin in the shuttle that has just been moved into its idle position. Such a strand of filling is shown in Fig. 1 at F. When this shuttle is again brought back into working position and makes its first pick, the thread or yarn F will be looped around the entire width of fabric which has been woven in the meantime. It is these loose loops of filling which the mechanism provided by the present invention is designed to trim off. Or, stated more accurately, the invention provides a mechanism which prevents the formation of most of these loops.

Stated briefly the mechanism shown includes means for gripping the filling thread running from the selvage of the goods to the bobbin in an idle shuttle and means for severing the thread so gripped at a point close to the selvage.

The mechanism shown in the drawings for grasping and holding the filling comprises a frame piece 6 which is supported on the lay and is secured by a bolt 7, Fig. 5, to the lay sword 4. This frame piece includes a member or block 6' which is cut away or grooved on its rearward side, as best shown in Figs. 5 and 6, the groove terminating in a notch 7 at the forward edge of the part 6'. It will be observed that this grooved member 6' is mounted immediately in front of the shuttle race and lies immediately beside the entrance to the shuttle box. Consequently, when a shuttle has been shot through the shed and into the drop box, and the pick of filling thus laid in the shed has been beaten up, the filling at that time will lie in approximately the position shown at F, Fig. 1. If the drop box 2 now is operated to move the shuttle into an idle position the strand of filling will be swung either up or down past the rearward surface of the part 6', the direction in which the filling is moved depending upon whether the drop box is raised or lowered. But the point where the filling crosses the forward

edge of the part 6' will still be somewhere in the notch 7.

Located immediately beside the front face of the part 6' and extending across the notch 7 is a gripper or clamping member 8. This member consists of a flat strip of resilient metal, preferably toothed on one edge, as shown at 9, Fig. 4, and provided at its upper end with a cylindrical shank portion 10 which projects through a short bracket 11 formed on the frame piece 6. This mounting of the gripper 8 permits it to rock slightly about the axis of the shank 10, but it is pressed against the front face of the part 6' by a short flat arm 12 clamped firmly in a holder 14 which is formed in the frame piece, the free end of this arm being turned backwardly at right angles and provided with a reduced tip which enters a slot formed in the gripper 8. A blade 15 is arranged to reciprocate or oscillate into and out of position between the gripper 8 and the front face of the block or extension 6'. The blade is secured by a screw 16 to an arm 17 having a mutilated gear 18 formed at one end thereof. This arm is secured fast on a rock shaft 20 which is supported in the frame 6 and is encircled by a coiled spring 21. The spring tends to hold the blade in the position shown in Figs. 5, 6 and 7 where the arm 17 rests on a part of the frame 6 which serves as a stop. The mutilated gear 18 meshes with the teeth of a rack 22 slidable vertically in the frame 6, and the upper end of this rack is arranged to be engaged by either one of two cams 24-24 formed on the lower side of a ratchet wheel 25, the teeth 26 of this wheel projecting from its upper edge. At an intermediate point the wheel is reduced and made of approximately square cross section with rounded corners, as indicated at 27, Fig. 3, and bars 28-28 are arranged to engage this flattened section of the wheel, the rearward ends of these bars being pivoted to the frame at 30-30, Fig. 3, while their forward ends are connected together by a coiled spring 31. The wheel is mounted on an upright shaft which is supported in a bearing formed in the frame 6.

In order to rotate this wheel step by step a pawl 32, Fig. 1, is adjustably mounted on the horizontal arm 33 of a bell crank lever fulcrumed at 34 on a bracket 35 which is adjustably secured to a part of the loom frame, as clearly shown in Fig. 1. This pawl may be adjusted vertically by turning a screw 36, Fig. 1, in or out, this screw being threaded through the upright arm 37 of said bell crank lever and bearing against the loom frame.

It will now be clear that when the loom is in operation the ratchet wheel 25 will be rotated one-quarter turn at each pick. This motion is imparted to the ratchet wheel as the lay swings backward, the movement being completed at approximately the time

that the lay reaches the backward limit of its stroke. If this motion occurs at a time when one of the cams 24 is in position to depress the rack 22 it will result in raising the blade 15 into approximately the position shown in Fig. 1. Due to the fact that there are only two cams 24 on the ratchet wheel the blade will be operated only on alternate picks, and the ratchet wheel is so set that this operation will occur after each pick in which the shuttle is delivered to the drop box 2. On the other picks the ratchet wheel is simply given an idle quarter turn movement. The arms 28-28 and spring 31 cooperate to prevent any overthrow of the ratchet wheel 25 and to stop its rotative movement at the end of each quarter turn. As the high point of one of the cams 24 passes over the upper end of the rack 22 the spring 21 immediately acts to snap the blade 15 into its downward or closed position where it rests between the parts 6' and 8, as shown in Figs. 4, 5 and 6. If when this movement of the blade occurs a strand of filling is positioned as shown in Fig. 1 where it runs from the selvage of the fabric to the bobbin in an idle shuttle in the box 2, the blade will catch this filling at an intermediate point and force a bight of the filling between the parts 6' and 8. This action is illustrated in Figs. 4 and 7. The yielding clamp or gripper 8 and the block 6' cooperate to grip this bight of filling securely and to hold it while the blade 15 is withdrawn from between the gripping members to make its next stroke. This gripping action of the parts is facilitated by the yielding or resilient character of the gripper 8 and by the fact that it is so supported that it can rock about a longitudinal axis and thus adjust itself either to the blade 15 or to the face of the part 6'. Each succeeding stroke of the blade forces the bight of the filling farther between the gripping members 6' and 8 until the end of the bight has passed beyond the teeth 9 on the gripper 8, thus positively preventing any possibility of withdrawing the filling by a movement toward the right, Fig. 4.

While the filling is held gripped in the manner just described, it is severed from the selvage of the fabric at a point close to the selvage. This severing or cutting operation can be performed by any suitable mechanism. The drawings show a temple cutter of an unique form used for this purpose. Referring to Figs. 1 and 2 the housing or casing for the temple will be observed at 40, the bracket which supports the temple at 41, and the stationary holder in which the bracket is mounted will be seen at 42. The bracket is provided with the usual plate 43 to be struck by the lay during its beat-up movement, the bracket being slidably mounted in the holder 42 in the usual manner. Supported on this bracket is a cutter of a type similar to a barber's clippers. That is, it comprises a series

of stationary teeth or cutters 44 and a co-operating series of movable teeth 45, the two series of teeth being held together in shearing relationship. The movable teeth are carried by a cutter head pivoted on the stud 46, Fig. 2, and provided with a shank 47 which is located immediately beside and slightly in advance of the plate 43 so that it will be struck by the lay just before the lay comes in contact with the plate 43 to operate the temple. The movement so imparted to the arm 47 is sufficient to give the movable teeth 45 their cutting stroke. A spring coiled about the rod 48 returns the arm 47 and teeth 45 to their initial positions as soon as the arm is released by the lay. This cutting mechanism thus operates immediately beside the selvage and has a rather wider range of action vertically than the ordinary temple cutter.

Assuming that a strand of filling has been gripped by the blade 15 and the members 8 and 6' which cooperate therewith, and that it is being held by the latter members substantially as shown at F in Fig. 1, it will be clear that this strand will be anchored in the cloth at a point immediately in front of the selvage cutter 44-45. The takeup movement of the cloth as the loom continues to operate will, after a very few picks, result in carrying this strand into the range of operation of the cutter which will sever it from the fabric. The length of filling between the gripping parts 6', 8 and the selvage of the goods will simply drop down into a position entirely out of the way of the operating mechanism. The gripping devices, however, will continue to hold the filling indefinitely providing the idle shuttle remains in the drop box, each closing of the blade 15 serving simply to crowd a very short additional length of the filling in between the gripping devices. Consequently, when the idle shuttle which carries the filling is again brought into operation and starts on its flight through the shed, the end of the filling will be properly gripped to cause the filling to be laid in the shed. If the shuttles are being changed very frequently, loops of filling may be formed with both ends anchored in the selvage, the loose part of the loop being held by the parts 6', 8 and 15 so that the anchored ends will be severed. Unless, however, the shuttle changes are quite frequent the formation of loops will be prevented.

Any possibility of clamping the filling in the running shuttle, or otherwise interfering with it, can readily be avoided by properly timing the closing movement of the blade 15. This may be done, as above described, by proper adjustment of the pawl 32. Preferably this adjustment is made such that the blade 15 is closed immediately after the working shuttle has left the box at the beginning of its flight through the shed.

It will thus be evident that the invention

provides an entirely automatic mechanism for trimming the loose threads from the selvage edge of the fabric at the drop box side of a box loom. The mechanism is relatively simple in construction and the parts are very strong and sturdy so that the device is extremely reliable. It requires no attention on the part of the machine attendant other than to keep it properly lubricated. As the loom continues to operate the severed threads drop clear of the machine and no trouble is experienced by the device loading up or clogging.

While we have herein shown and described a preferred embodiment of our invention it will be understood that the invention may be embodied in other forms without departing from the spirit or scope thereof.

Having thus described our invention, what we desire to claim as new is:

1. In a box loom, the combination of means mounted on the lay of the loom for gripping a strand of filling running from the selvage of the fabric to the bobbin in an idle shuttle in the drop box, mechanism for utilizing the motion of the lay to operate said means, and mechanism for severing the strand of filling so gripped close to the selvage of the goods.

2. In a box loom, the combination of means mounted on the lay of the loom for gripping a strand of filling, mechanism for supporting said means in position for engagement with the filling running from the selvage of the fabric to a shuttle thrown out of action at the box side of the loom, mechanism for operating said means immediately following each pick only in which the shuttle is delivered to the box side of the loom, and mechanism for severing the filling so gripped at a point close to the selvage.

3. In a box loom, the combination of relatively movable parts mounted on the lay of the loom for gripping and holding a strand of filling at a point between the selvage edge of the fabric and an idle shuttle in the drop box, mechanism for operating one of said parts to give it a gripping movement between the time that the working shuttle starts from the box side of the loom on its flight through the shed and returns again to the box, and means for cutting the strand so gripped at a point close to the selvage of the goods.

4. In a box loom, the combination of relatively movable parts mounted on the lay of the loom for gripping and holding a strand of filling at a point between the selvage edge of the fabric and an idle shuttle in the drop box, mechanism for operating one of said parts to give it a gripping movement while the lay is at the backward part of its stroke and immediately after the working shuttle has left the box side of the loom on its flight through the shed, and means for severing the strand so gripped at a point close to the selvage of the goods.

5. In a box loom, the combination of parts

mounted on the lay of the loom for gripping and holding a strand of filling, a blade co-operating with said parts to force a bight of filling into gripping relationship to said parts, mechanism for operating said blade to cause it to engage a strand of filling running from the selvage of the goods to an idle boxed shuttle, and means supported on the breast beam for severing the strand of thread 10 so gripped at a point close to the selvage of the goods.

6. In a box loom, the combination of parts for gripping and holding a strand of filling, a blade cooperating with said parts to force 15 a bight of filling into gripping relationship to said parts, means mounted on the lay of the loom for supporting said parts and said blade, mechanism for utilizing the movement of the lay to operate said blade and to cause 20 it to engage a strand of filling running from the selvage of the fabric to an idle boxed shuttle, and mechanism for cutting said strand at a point close to the selvage of the goods.

25 7. In a box loom, the combination of relatively yielding parts for gripping and holding a bight of filling, a reciprocating blade cooperating with said parts to force a bight of filling between them, means mounted on 30 the lay of the loom for supporting said parts and said blade, and mechanism for utilizing the movement of the lay to reciprocate said blade.

35 8. In a box loom, the combination of relatively yielding parts for gripping and holding a bight of filling, a reciprocating blade cooperating with said parts to force a bight of filling between them, means mounted on the lay of the loom for supporting said parts and 40 said blade, and mechanism for operating said blade including a cam and a pawl and ratchet mechanism arranged to be operated by the motion of the lay for giving said cam its operative movement.

45 9. In a box loom, the combination of relatively yielding parts for gripping and holding a bight of filling, a reciprocating blade cooperating with said parts to force a bight of filling between them, said parts being constructed to prevent any substantial withdrawal movement of the filling with the blade, means mounted on the lay of the loom for supporting said parts and said blade, and mechanism for operating said blade including a spring for closing the blade, a cam for opening it, and means for utilizing the motion of the lay to operate said cam.

50 10. In a box loom, the combination of means mounted on the lay of the loom for gripping a strand of filling extending from the selvage of the fabric to the bobbin in a boxed shuttle at the box side of the loom, said means comprising relatively movable thread gripping parts located in front of the 55 path of travel of the working shuttle, and

cutting means located at the selvage of the fabric and arranged to sever the filling so gripped when it is brought into the range of operation of said cutting means by the take-up movement of the fabric.

70 In testimony whereof we have hereunto signed our names to this specification.

WILLIAM J. INGHAM.
JOSEPH LAROUCHE.
